LAMP FOR INDICATING OPERATION OF DIRECTIONAL SIGNALS OR SIMILAR ARTICLE

Marshall Homer Alldredge, 1050 Woodlea Road,
Birmingham, Mich.

Filed Apr. 14, 1964, Ser. No. 79,487

Term of patent 14 years

(Cl. D48—32)

FIGURE 1 is an isometric view of a lamp for indicating operation of directional signals showing my new design and taken on a reduced scale.

FIGURE 2 is a side elevational view thereof.

FIGURE 3 is a bottom plan view thereof.

FIGURE 4 is a top plan view thereof.

FIGURE 5 is a rear end view thereof.

FIGURE 6 is a front end view thereof.

The dominant features of my design reside in the portions shown in full lines, the broken lines in FIG. 1 being for illustrative purposes only.

I claim:

The ornamental design for a lamp for indicating operation of directional signals or similar article, substantially as shown and described.
